MIXER

Arnet Theodore Jolma, St. Helens, Oreg.

Application November 18, 1935, Serial No. 50,441

2 Claims. (Cl. 259—113)

This invention relates to an improved mixer by means of which coloring matter may be mixed with nucoa, oleomargarin and other greasy or plastic substances which are manufactured in an uncolored state and are sold together with a coloring substance to be mixed therewith by the purchaser before being used. It will be obvious that while the device is primarily intended for mixing coloring matter with a greasy or plastic substance, the device may be used for mixing any substance of a similar texture which should be thoroughly mixed before being used.

One object of the invention is to provide a device of this character including a housing and a piston mounted for reciprocating movement longitudinally therein, the housing being so constructed that the material to be mixed may be easily placed therein and the housing then closed and the piston being of such construction that as it reciprocates in the housing, the material may have circulating movement through the piston and thus cause the material to have such movement imparted to it that it will be thoroughly mixed and coloring matter evenly distributed throughout the mass of greasy or plastic substance.

Another object of the invention is to provide the device with a piston having means associated therewith for controlling movement of the greasy or plastic material through the piston according to the direction in which the piston is moving.

The invention is illustrated in the accompanying drawing, wherein

Figure 1 is a view showing the improved mixer secured upon a table or other support and shown partially in side elevation and partially in longitudinal section.

Figure 2 is a sectional view taken transversely through the housing of the mixer along the line 2—2 of Figure 1.

Figure 3 is a fragmentary longitudinal sectional view taken along the line 3—3 of Figure 2.

This mixer has a base 1 in the form of an elongated strip of wood, metal, porcelain or any other desired material, and upon one end portion of the base is mounted a housing 2 which may also be formed of any desired material and secured to the base in any manner desired. The housing preferably corresponds in width to the base and is rectangular in cross section, as shown in Figure 2, and of appreciably greater length than width. A clamp 3 is secured against a side edge face of the base in spaced relation to the inner or rear end of the housing and extends in depending relation to the base so that when the mixer is set in

place upon a table 4 and the set screw 5 of the clamp tightened, to engage the under face of the table top, the mixer will be securely but detachably held firmly in place upon the table. The housing has an open outer or forward end so that a print of oleomargarin or other greasy or plastic material may be thrust into the housing and the open end of the housing then closed by a removable front wall or head 6 which fits against forward ends of walls of the housing with a portion 10 fitting snugly in the housing, as shown in Figure 1. A plate 7 of metal extends transversely across the outer face of the head 6 and has its end portions formed with openings or slots to receive securing bolts 8 and referring to Figures 1 and 3 it will be seen that these bolts have their rear ends formed with eyes 9 loosely engaged about studs or pins 10 projecting from side walls of the housing. The forward end portions of the bolts are threaded to receive winged nuts 11 and it will be readily understood that when the bolts are engaged through the plate 7 and the nuts tightened, the head 6 will be firmly secured in closing relation to the open forward end of the housing. Therefore, when a print of oleomargarin or the like is placed in the housing, together with coloring matter and the head set in place and secured, there will be no danger of the material escaping during the mixing operation.

A piston 12 which conforms to the interior dimensions of the housing is slidably received therein and at its center is formed with a threaded opening 13 to receive the reduced and threaded forward end 14 of a piston rod or bar 15 which extends longitudinally of the housing through an opening 16 formed in the rear or inner end wall of the housing. This rod or bar is rectangular in cross section and has its outer or rear end portion formed with teeth to provide a rack 17 engaged by a gear or pinion 18 which is rotatably mounted between the arms 19 of a bracket 20 and provided with a handle 21 by means of which the pinion may be rotated and reciprocating movement imparted to the shaft 15 and piston 12. The bracket is secured upon the base 1 by screws 45 or bolts 21 and its arms not only rotatably support the pinion 18 but also carry a pinion or shaft 22 upon which a roller 23 is mounted. This roller is disposed under the bar or piston rod 15 to serve as a support for the outer portion thereof and permit the bar to slide easily. It will be understood that the rack will be of sufficient length to permit the piston to travel the entire length of the housing from the open front or outer end thereof to its closed rear or inner end and thus 55

eliminate likelihood of the greasy or plastic material accumulating in the inner end portion of the housing and also permitting the material to be completely ejected through the forward end of the housing after the mixing operation has been completed and the head 6 removed.

During operation of the mixer, the greasy or plastic material is to move through the piston as the piston reciprocates in the housing and, therefore, the piston has been formed with openings 24 and 25 located in spaced relation to opposite sides of the shaft or piston rod. Plates 26 and 27 are pivotally mounted in the openings 24 and 25 upon pins 28 and 29 extending vertically therein and by referring to Figure 3 it will be seen that the pin 28 is located adjacent the rear end of the opening 24, whereas the pin 29 is located adjacent the forward end of the opening 25. Therefore, the plate 26 extends forwardly from the pin 28 and the plate 27 extends through the opening 25 rearwardly from the pin 29. The free end portions of the two plates are beveled, as shown at 30 and 31, and, therefore, when the piston is in motion and traveling forwardly, the beveled surface 30 of the plate 26 will cause a cam action to take place and swing this plate transversely across the opening 24 shown in Figure 3 to a position in which it partially blocks the opening, whereas the plate 27 will extend in centered relation to the opening 25 and permit the greasy or plastic material to pass through the opening 25 at opposite sides of the plate 27. As the piston moves rearwardly, the plate 27 will be swung into position to partially block the opening 25 and the plate 26 disposed in centered relation to the opening 24. It will thus be seen that during reciprocating movement of the piston, the plastic material may move through one of its openings with greater ease than it does through the other opening and the plastic material will be circulated in the housing and the coloring matter thoroughly intermingled with the plastic material. After the coloring matter has been thoroughly intermingled with the greasy or plastic mass, the nuts 11 may be loosened and the bolts 8 moved out of engagement with the plates 7 so that the head 6 may be removed and additional reciprocating movement

imparted to the piston and thus cause the greasy or plastic material to be ejected from the open forward end of the housing. The clamp holding the mixer upon the table can then be loosened and the mixer thoroughly cleaned and put away 5 until again needed.

Having thus described the invention, what is claimed as new is:

1. A mixing device comprising an elongated casing, a piston slideable longitudinally in said casing and having a piston rod extending through one end of the casing, said piston having openings formed therein whereby material in the casing may pass through the piston as the piston moves longitudinally in the casing during a mixing operation, plates pivotally mounted in the openings of the piston and extending longitudinally of the casing with the plate in one opening having its free end extending longitudinally of the casing in an opposite direction to the free 20 end of the plate in a second opening, the free end portions of the plates being provided with cam surfaces whereby as the piston moves longitudinally one of the plates will be moved transversely into position to retard movement of material 25 through an opening of the piston, and means for imparting reciprocating movement to the piston rod and piston.

2. A mixing device comprising a base, an elongated casing carried by the base and extending 30 longitudinally thereof with its inner end spaced from one end of the base, a piston slideable longitudinally in said casing and formed with openings for passage of material through the piston as the piston reciprocates in the casing, a rod extending from said piston through the inner end of the casing, a bracket carried by the base in spaced relation to the inner end of the casing, a roller carried by said bracket with said rod resting thereon to support the outer end portion of the 40 rod, the upper portion of the rod being provided with rack teeth, a pinion carried by said bracket over the rod and meshing with the rack teeth, and means for rotating the pinion and imparting reciprocating movement to the rod and piston. 45
